(57) **CLAIM**

The ornamental design for a humidifier as shown and described.

DESCRIPTION

FIG. 1 is a front, left and top perspective view of a humidifier, showing our design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a slit; and,

FIG. 10 is a front, left and bottom perspective view of the humidifier of FIG. 1 wherein an upper part and a lower part are shown separately.

The broken lines shown in the drawings are included for the purpose of illustrating portions of the humidifier that form no part of the claimed design.

The dot-dash broken lines encircling portions of the humidifier indicate enlargement boundaries and form no part of the claimed design.
